UNITED STATES PATENT OFFICE.

AUGUST SCHAEFER, OF NEW YORK, N. Y., ASSIGNOR OF ONE-HALF TO ADELE BALTHEISER, OF NEW YORK, N. Y.

DESIGN FOR A BOX.

Application filed December 9, 1924. Serial No. 11,626. Term of patent 14 years.

To all whom it may concern:

Be it known that I, AUGUST SCHAEFER, my new design. a citizen of Germany, residing in New York city, in the county and State of New York, have invented a new, original, and ornamental Design for a Box, of which the following is a specification, reference being had to the accompanying drawing, forming part thereof.

I claim:

The ornamental design for a box, as shown.

AUGUST SCHAEFER.
